UNITED STATES PATENT OFFICE.

LINCOLN BARKER, OF NEW YORK, N. Y., ASSIGNOR TO TRIPPE, BARKER & CO., OF NEW YORK, N. Y., A CORPORATION OF NEW YORK.

DESIGN FOR A TEXTILE FABRIC.

Application filed February 20, 1928. Serial No. 25,499. Term of patent 3½ years.

To all whom it may concern:

Be it known that I, LINCOLN BARKER, a citizen of the United States, residing in New York, in the county of New York, State of New York, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

LINCOLN BARKER.
